UNITED STATES PATENT OFFICE

CHESTER B. SHEPARD, OF MELROSE, MASSACHUSETTS, ASSIGNOR TO
GEORGE E. FEAGANS, OF JOLIET, ILLINOIS.

DESIGN FOR A HANDLE FOR SPOONS, FORKS, OR SIMILAR ARTICLES.

No. 37,932.

Specification for Design.

Patented April 3, 1906.

Application filed February 28, 1906. Serial No. 303,540. Term of patent 3½ years.

To all whom it may concern:

Be it known that I, CHESTER B. SHEPARD, a citizen of the United States, and a resident of Melrose, in the county of Middlesex and Commonwealth of Massachusetts, have invented a new, original, and ornamental Design for a Handle of a Spoon, Fork, or Similar Article, of which the following is a specification, reference being had to the accompanying drawings, forming part hereof, in which—

Figure 1 is a front view, and Fig. 2 a back view, of said design.

What I claim is—

The ornamental design for a handle of a spoon, fork, or similar article, as shown.

CHESTER B. SHEPARD.
